REVERSING MECHANISM

Nelson S. Campbell, Brookline, Mass.

Application April 9, 1941, Serial No. 387,637
In Canada September 7, 1940

5 Claims. (Cl. 74—70)

This invention relates to a mechanism for delivering rotary motion alternatively in opposite directions from rotary motion continuously imparted to it in one direction.

Heretofore in the operation of some machinery, such as some textile machinery, it has been desirable to impart opposite reciprocating or rotary motion to some part, and to do this, means have been provided which have considerable slap of parts making a great deal of noise and requiring them to be made of rather large and cumbersome size in order that the strength may be had for their proper support. These cumbersome and noisy forms of mechanism for accomplishing this result are expensive to construct. A crank motion is commonly employed for delivering such reciprocating motion, and the reciprocating motion delivered from a crank, as is well known, is not of a uniform speed throughout the straight line motion delivered in opposite directions.

One of the objects of this invention is to minimize these undesirable results set forth in the preceding paragraph.

Another object of the invention is the provision of a simple form of mechanism for accomplishing this result and one which may be made small in size.

Another object of this invention is to provide a reciprocating mechanism in which there will be delivered a uniform speed of travel from the beginning to the end of motion in each direction.

Another object of the invention is the provision of a reciprocating motion in which the reverse will be immediate and a constant rate of travel will be had throughout the straight line travel of motion in each direction.

Another object of the invention is to provide a device for delivering rotary motion alternatively in opposite directions which will be so constructed that it will be quiet in its operation and may be readily lubricated.

The invention consists in the provision of all rotary parts with the transmission of power through a helical gear action.

With these and other objects in view, the invention consists of certain novel features of construction, as will be more fully described, and particularly pointed out in the appended claims.

In the accompanying drawing:

Fig. 1 is a sectional view of the casing, showing in plan the operating arrangement of my mechanism;

Fig. 2 is a section on line 2—2 of Fig. 1; and

Fig. 3 is a view looking as from line 3—3 of Fig. 1.

With reference to the drawing, I have provided a casing 200 in the form of a rectangular box in which there are parallel shafts 201, 202 on either side of a shaft 203 parallel to these shafts and located between them. These shafts are all mounted in suitable bearings indicated by the provision of bosses 210 on the outer surface of the casing. A shaft 204 has a gear 205 fixed upon one of its ends, which gear receives a continuous driving rotary motion from some suitable connection such, for instance, as that illustrated in my copending application Serial No. 340,415, dated June 14, 1940. Shaft 204 is equipped with opposite spiral gears 206 and 207. Gear 206 meshes with spiral gear 208 on shaft 201, and spiral gear 207 meshes with spiral gear 209 on shaft 202 so as to provide opposite drive to these shafts 201 and 202 in unison. A cylindrical member 211 is mounted upon shaft 201, and a cylindrical member 212 is mounted upon shaft 202, each with a single helical tooth 213 and 214 extending one-half of the revolution of the rotary member of drum 211 or 212. These teeth 213 and 214 are positioned oppositely. The shaft 203 is provided with a cylindrical member or drum 215 upon which there is a helical tooth 216 which extends a complete revolution thereabout and has the same pitch as the pitch of the teeth 213 and 214.

The position of the members 211 and 212 are such that when drive is being imparted from cylinder 211 to cylinder 215, by reason of the engagement of the teeth 213 and 216, the non-toothed surface of the cylindrical member 212 will be toward the member 215, and when the end of tooth 213 passes out of engagement with the tooth 216, then the tooth 214 will pick up the tooth 216 to impart an opposite drive to the member 215, while the non-toothed surface of the member 212 is toward the member 215. Thus, there will be delivered to shaft 203 opposite alternate rotation which may be transferred through the gear 217 to some desired part which the mechanism is to drive, such, for instance, as the reciprocating motion of the twist controller set forth in my copending application above referred to.

The shaft 204 is suitably supported in bearings 218 supported at the end of brackets 219 from the casing 200. By reason of enclosure of these cylindrical drum members in the casing 200, they may operate in a lubricant and by reason of the

spiral gear relationship, the parts will run smoothly and quietly.

Because of the uniform helical pitch of the interengaging teeth, the motion imparted in one direction will be at a constant rate and because of the same uniform opposite pitch of the tooth on a member traveling in the opposite direction, there will be the same constant rate in the opposite direction; and as the tooth of one member disengages and the tooth of the other member engages the tooth of the center member at substantially the same instant, the reverse will be immediate, and the same constant rate in the opposite direction will be picked up immediately for delivery from the mechanism.

I claim:

1. A mechanism for delivering rotation in opposite directions comprising a cylindrical driven member rotatably mounted on its axis and having a tooth helically disposed about its surface for substantially one revolution thereof, a pair of driving members located with one on either side of said driven member and each having a tooth helically disposed substantially one-half revolution and extending substantially half the length of the axial extent of the tooth of the driven member, said driving members being so positioned as to have their teeth alternately engage the tooth of the driven member, and means for oppositely rotating said driving members whereby the driven member will be alternately oppositely rotated.

2. A mechanism for delivering rotation in opposite directions comprising three cylindrical members each rotatable about a separate axis, spaced from each other and extending in parallel relation and in a plane passing centrally through all of said axes, means for oppositely rotating the outer members continuously in one direction, and helically-disposed means interconnecting said members for transmitting alternatively opposite rotation to the intermediate member.

3. A mechanism for delivering rotation in opposite directions comprising a single cylindrical

driven member rotatably mounted on its axis and having a single tooth helically disposed about its surface for substantially one revolution thereof, a pair of driving members located with one on either side of said driven member and each having a single tooth helically disposed substantially one-half revolution and extending substantially half the length of the axial extent of the tooth of the driven member, said driving members being so positioned as to have their teeth alternately engage the tooth of the driven member, and means for oppositely rotating said driving members whereby the driven member will be alternately oppositely rotated.

15 4. A mechanism for delivering rotation in opposite directions comprising a cylindrical driven member rotatably mounted on its axis and having a single tooth helically disposed about its surface for substantially one revolution thereof, a pair of driving members located with one on either side of said driven member and each having a single tooth helically disposed substantially one-half revolution and extending substantially half the length of the axial extent of the tooth of the driven member, said driving members being so positioned as to have their teeth alternately engage the tooth of the driven member, and means for oppositely rotating said driving members whereby the driven member will be alternately oppositely rotated.

30 5. A mechanism for delivering rotation in opposite directions comprising three cylindrical members one intermediate of the other two outer members, each rotatable about a separate axis which axes are spaced from each other and extend in parallel relation, means for oppositely rotating the outer members continuously in one direction, and a single helically-disposed tooth on each member interconnecting said outer members with the intermediate member for transmitting alternatively opposite rotation to the intermediate member.
